UNITED STATES PATENT OFFICE.

CONRAD ESPING, OF MOLINE, ILLINOIS, ASSIGNOR TO MCLINE PLOW COMPANY, A CORPORATION OF ILLINOIS.

BEET-PULLING MACHINE.

1,323,683.

Specification of Letters Patent.

Patented Dec. 2, 1919.

Original application filed May 5, 1917, Serial No. 166,670. Divided and this application filed February 5, 1919. Serial No. 275,094.

To all whom it may concern:

Be it known that I, CONRAD ESPING, a citizen of the United States, residing at Moline, in the county of Rock Island and State of Illinois, have invented certain new and useful Improvements in Beet-Pulling Machines, of which the following is a specification, reference being had therein to the accompanying drawing, being a division of original application filed May 5, 1917, Serial No. 166,670.

This invention relates to beet pulling machines of the type embodying a wheeled frame equipped with beet pulling elements, which, in the travel of the machine, act beneath the surface of the soil and, engaging the beet roots, automatically lift the same as the machine advances; and the invention consists of various improvements in the form, construction and mounting of the beet pulling elements, which improvements will be fully described in the specification to follow, and the novel features of which will be set forth in the appended claims.

In the accompanying drawings:

Figure 1 is a top plan view of a beet pulling machine having my invention embodied therein.

Fig. 2 is a side elevation of the same.

Fig. 3 is a transverse sectional elevation of the same as viewed from the front.

Fig. 4 is a transverse sectional elevation through the beet pulling elements on the line 4—4 of Fig. 2.

Fig. 5 is a perspective view of the parts of one of the beet pulling elements separated from each other.

Referring to the drawings:

1 indicates the machine frame, in the present instance of horizontal rectangular open form and comprising fore-and-aft extending parallel side frame bars 2, a front frame bar 3 connecting the forward ends of the frame bars 2, and a rear frame bar 4 connecting the rear ends of the frame bars 2. At its rear the frame is supported by two ground wheels 5, and at its front by two caster or guide wheels 6, this arrangement producing a wheeled frame on which are mounted beet pulling elements 7 with which the present invention is particularly concerned.

These beet pulling elements, of which there are two as usual, are fixed to the lower

ends of standards 8 which extend upwardly 55 at a rearward inclination and diverge toward their upper ends where they are rigidly fixed to the side bars 2 of the frame near the rear ends of the same. The standards are flat, are disposed edgewise in a fore-and-aft direction, and are adapted to be adjusted to and from each other so as to vary the space between the pulling elements to adapt the latter for operation on different sized beet roots. The adjustment of the standards is effected by means of adjusting devices, in the present instance in the form of upright rods 9, the lower ends of which are bolted or otherwise secured to the inner sides of the respective standards as at 10, and the upper ends of which are threaded and extend through inwardly extending horizontal brackets 11 fixed respectively to the side bars of the frame, confining nuts 12 and 13 being screwed on the threaded ends of the rods 70 and engaging respectively against the opposite sides of the brackets. By means of these nuts the adjusting rods may be shifted endwise in the brackets and caused to either pull the standards toward each other or spread them apart, according to the direction of movement of the nuts, with the result that the pulling elements on the lower ends of the standards will be correspondingly adjusted to vary the space between them. The action of these adjusting rods is to spring the standards to or from each other, which insures the fixed, firm and rigid support of the standards in their different 85 positions and avoids any possibility of looseness or accidental displacement which would be apt to occur were the standards pivoted or mounted to rock to effect their adjustments.

As shown more particularly in Figs. 1, 95 4 and 5, the pulling elements 7 are in the form of horizontally disposed plates fixedly connected about midway of their ends, to the lower ends of the standards so that they will extend both in front and in rear of the same. As these plates are identical in form and construction, a description of one will suffice. Each plate comprises a vertical portion 7^a which is secured flatly to the inner side of the inturned lower end 8^a of 100 its standard, from which point the lower edge of the plate extends forwardly in a substantially straight line 7^b to its forward

extremity. The lower edge extends rearwardly from the central portion 7^a in an upward curve as at 7^c for a short distance and then extends to the rear extremity of the plate in a horizontal line 7^a which is at a higher level than the line 7^b. The upper edge of the rear portion of the plate is curved laterally outwardly, thereby forming a rounded overhanging flange 7^c, the outer edge of which extends at an inclination toward the front of the plate and terminates at the vertical central portion 7^a. From this point to the front end of the plate, the upper edge curves downwardly as at 7^c. The plates of this specific form are applied to the lower ends of the standard so that their inner adjacent faces or sides will converge toward each other in a rearward direction, the space between the plates being therefore widest at the front and gradually contracting toward the rear so as to present a passage or space between them of gradually decreasing width, and the upper edges of the plates incline generally upwardly in a rearward direction. As a result of the formation and the relative disposition of these plates, their forward points will, as the machine advances, penetrate the soil on opposite sides of the beet root and loosen the same, and as their movement continues, the beet will pass into the gradually contracting space between the plates and will be engaged by the inner curved portions of the flanges 7^c, and, owing to the upward slope of these surfaces, the beet will be lifted from the ground and be discharged from the rear ends of the plates. The rounded edges of the plates formed by the outturned flanges, present smooth surfaces for engagement with the beet root and thereby prevent injury to the same.

In order to prevent wear on the forward edges of the standards above the pulling elements, at the points where in the action of the machine the standards pass through the ground, wear plates 9^a are applied as shown more particularly in Figs. 2, 3 and 4. These plates are of flat form and slotted in their rear edges as at 9^a to receive the forward edges of the standards, and are fastened to the standards by means of a fastening bolt 9^b passing through ears 9^c pro-

jecting rearwardly from the plate and through the edge of the standards between them, the lower ends of the wear plates being extended inwardly so as to overlie the upper edges of the pulling elements as shown in Fig. 5.

In the foregoing description and accompanying drawings I have set forth my invention in the particular form and embodiment as to the details of the construction thereof which in practice I prefer to adopt and which has been found to answer to a satisfactory degree the ends aimed at. It will be manifest that various changes in the construction such as would suggest themselves to the skilled mechanic may be made without departing from the limits of my invention; and further it will be understood that the invention is not limited to any particular form or construction of the parts except in so far as such limitations are specified in the claims.

Having thus described my invention, what I claim is:

1. A beet pulling element for a beet pulling machine, said element comprising a plate having an upright portion inclined at its upper edge downwardly toward the front, and provided in rear of said inclined portion with a curved flange projecting laterally outwardly from the upper edge of the plate.

2. In a beet pulling machine, the combination of beet pulling elements comprising opposing plates having upright faces presented toward each other between which the beet root is received, and having rounded surfaces on the upper edges of said plates to engage the beet.

3. In a beet pulling machine, the combination of pulling elements comprising opposing plates converging rearwardly toward each other and each provided with an upright portion having on its upper edge an outwardly curved flange, the outer edge of which flange extends at an inclination toward the front of the plate and terminates at the upright portion thereof, and the edge of the plate at the front being inclined downwardly and forwardly.

In testimony whereof, I have affixed my signature hereto.

CONRAD ESPING.
